FASTENER FOR WRIST BANDS

Chester A. Page, Bay Shore, N. Y.

Application March 27, 1947, Serial No. 737,470

1 Claim. (Cl. 24—201)

1

This invention relates to an improved band fastener and particularly to fastening means for a resiliently flexible severed strip.

The invention is particularly useful in connection with metal bands for wrist watches and will be illustrated in detail by description in connection with such use.

As compared to metal wrist bands heretofore known, I provide a simpler construction and one of different pleasing appearance. I fashion the parts of the fastening means from the strip metal itself. I require no buckle, rivet, loop, or other added accessories. I make possible a union of the two ends of the wrist band in which the meeting ends lie flush with each other so as to give the appearance of general smoothness of surface, simplicity of construction, and attractiveness of appearance. At the same time the details of construction and the springiness of the material selected for the band make the closure positive and subject to release by simply overcoming, at the position of union of the ends, the outwardly directed springiness of the metal band, as by pressure with the thumb upon the union.

The invention comprises the herein described article including a severed resiliently flexible strip, one end of which has an upstanding tab and a portion provided with a transverse slot located a short distance from the actual end and the other end of which has a tongue of reduced width to slip through the said slot and is provided with an opening of size and space to receive this upstanding tab when the tongue is engaged in the slot. In the preferred embodiment of the invention the tongue and also the portion provided with the slot are offset with respect to the rest of the band, suitably by about equal amounts, the offsets being in directions that are the same when the two ends are assembled. This direction is preferably toward the wrist of the wearer so that the straight portions of the two ends are flush when the tongue is inserted through the slot.

The invention will be further illustrated by description in connection with the attached drawing to which reference is made.

Fig. 1 is a sectional view of the band as used to hold a wrist watch and with the band in closed position.

Fig. 2 is a plan view of the assembled ends of the wrist band.

Fig. 3 is a view similar to that of Fig. 1 with the wrist band in open position.

2

Fig. 4 is an end view of the assembly of Fig. 3, that is with the wrist band in open position.

Fig. 5 is a perspective view of the end of the wrist band provided with tabs and slot.

5 Fig. 6 is a perspective view of the other end of the wrist band namely the part provided with tongue and openings to receive the tabs in the finished assembly.

The views in Figs. 1, 3, and 4 are partly diagrammatic and parts not shown in detail are conventional.

There is shown a wrist watch 8 and wrist band indicated generally at 9. The wrist band is severed. The two ends thereof, that is, the parts which are involved in the opening and closing of the wrist band are illustrated in detail in Figs. 5 and 6. One end is provided with a slope 10 between the band proper and the offset end portion 11 thereof. This same portion is provided at its ends with an upstanding tab and preferably with the spaced tabs 14 which are turned up from the side edges of the end of the offset part.

20 The other end 15 terminates in the tongue 16 of reduced width as compared to the rest of the band and joined to the band by the sloping portion 18. This same end is provided with an opening or openings such as the notches 20 in the side edges of the strip.

The band is preferably preshaped to correspond roughly to the curvature of the wrist of the wearer but so that the two ends 11 and 15 must be flexed in the direction of the wrist of the wearer and against the natural resilience of the material of the band for union of the ends 35 of it.

In closing the band around the wrist the band is applied in open position, the two ends brought together and the tongue 16 inserted through slot 12, the slot being slightly oversize with respect to the cross sectional dimensions of tongue 16. Likewise the notches 20 which are slightly oversize with respect to the turned up tabs 14 on the other hand are spaced from each other by about the same distance as the tabs 14 and from the 45 position of abutment of sloping portion 18 of the tongue with sloping portion 10 provided with a slot by a distance approximately equal to the spacing of tabs 14 from the position of said abutment. In other words, tabs 14 and apertures 50 20 are spaced about equally from the sloping portions 10 and 18 respectively.

The result is that the tabs register with the openings 20 and extend therethrough. The lapping of the portions 11 and 15 and the engagement of the tongue 16 within the slot 12 keep

the band in alignment. Also the springiness of the metal which constantly presses the lapped portion 11 at one end against the lapped portion 15 of the other end forces the tabs outwardly so that their engagement with the openings 20 is made positive.

To release the engagement it is necessary only to press inwardly on part 15 (Fig. 1) until the flexing of the part 15 depresses the part 11 of the other end until the points 14 disengage from openings 20. Then the two parts of the wrist band are easily pulled apart.

Tabs 14 extend at an angle from the edge of the end of part 11 in the direction that is outward when the band is assembled on the wrist of the wearer. The angle made between the tabs and the general plane of part 11 is suitably about a right angle although the tabs may be slightly curved and concave on the side towards the part 11.

The part 11 which carries the tabs is offset from the band in direction opposite that of the extension of the tabs 14.

On the other end the tongue 16 is offset also towards the wrist of the wearer when the band is assembled, that is, in the same direction in the finished assembly as the part 11. The result is abutment of the sloping parts 10 and 18 when the tongue 16 is inserted through the slot as shown in Figs. 1 and 2. Preferably the amount of offsetting of the one end provided with the slot and the tongue on the other end is about equal so that the band forms a flush joint at the meeting point which is at the position of the slot indicated by reference character 12 in Figs. 1 and 2.

It will be observed that all of the elements involved in the fastening are shaped from or formed in the strip material of which the band is composed. No added accessory is required. The result is a union that is practically as smooth as the remainder of the band with the exception of the very slight protuberance of tabs 14 beyond the notches 20 and a line of union at the position 12 and corresponding to the position of the slot in the assemblies of Figs. 1 and 2. The closure means have the appearance of lightness and simplicity which is very desirable. Furthermore, the smoothness of the exterior of the joined portions prevents objectionable catching of the closure means on clothing.

As the material of construction of the wrist band 9 there is used suitably spring strip steel of about the resiliency and flexibility ordinarily found in clock springs. The material is cut and shaped and provided with the cut outs forming the slot 12 and the notches 20 in conventional manner.

Other material of construction may be used including a plastic band of sufficient resiliency and stiffness to show outward spring pressure on the points 14 in the assembly of Figs. 1 and 2. An example of such plastic is a springy, rather stiff cellulose acetate strip. Phosphor-bronze strip may also be used.

While the article has been illustrated by description in connection with a wrist band, the article may be used also as a belt, bracelet or necklace. In such use all parts are conventional with the exception of the closure means such as illustrated in Figs. 2, 5, and 6, in which the band is otherwise a continuous strip of metal without the inclusion of watch 8. In place of a watch there may be inserted if desired any conventional type of ornament held in the band in the usual type of union.

It will be understood that it is intended to cover all changes and modifications of the example of the invention herein chosen for the purpose of illustration which do not constitute departures from the spirit and scope of the invention.

What I claim is:

A wrist band comprising a resiliently flexible severed strip of material, a terminal on one end of the strip, a tab upstanding at approximately a right angle from the terminal and in direction away from the wrist when the band is in use, a second end portion of the strip provided with an opening of size to receive the tab, the sides of the opening conforming with the surface of the strip at that point, a tongue extending from the said second end portion of the band, an offset portion of the terminal first mentioned in the direction of the wrist from the adjacent portion of the strip, and a connecting part extending in sloping manner between the said terminal and the said offset portion of the strip and provided with a slot of width to receive the said tongue, the band described automatically locking itself when the tongue is inserted through the said slot and the said tab caused to register with the said notch.
